UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

TURNBUTTON FASTENER.

1,417,658.

Specification of Letters Patent. Patented May 30, 1922.

Application filed February 16, 1921. Serial No. 445,353.

To all whom it may concern:

Be it known that I, DAVID BOURQUE, a citizen of the United States, and a resident of Amesbury, county of Essex, and State 5 of Massachusetts, have invented an Improvement in Turnbutton Fasteners, of which the following description, in connection with the accompanying drawings, is a specification, like characters on the drawings representing like parts.

This invention relates to fasteners of the turnbutton type such as are commonly used for securing the curtains of automobiles to the frame and for similar purposes. One of 15 the primary objects of the invention is the provision of such a fastener which will be exceedingly compact and not project unduly from the work and which will hold the curtain or other member snug.

20 My invention may best be understood by reference to the following description of the embodiment thereof shown by way of example in the accompanying drawings, wherein:

25 Fig. 1 is a central vertical section through the parts of the fastener in engaged position;

Fig. 2 is a plan view of the eyelet;

Fig. 3 is a section on the line 3—3 of 30 Fig. 2;

Fig. 4 is a rear view of the button member;

Fig. 5 is a rear view of the head element detached;

Fig. 6 is a plan thereof; and

35 Fig. 7 is a section on line 7—7 of Fig. 6.

A fastener of the turnbutton type comprises two elements, the button element and the eyelet. The former is usually secured to a fixed support such as the frame of the vehicle and the latter to some member such as the curtain of an automobile which it is to secure thereto. Referring to Fig. 1 the button member shown comprises an oblate base or body 10 adapted to be encircled by the eyelet and a head or button proper 12 rotatably mounted thereon; preferably by yielding means as hereafter described. When the head 12 is aligned with the base it may pass through a corresponding oblate opening in an eyelet 14 and thereafter be turned to be parallel to the shorter dimension of such eyelet to overlie the sides thereof and hold it in its position encircling the body 10.

In carrying out my invention in the man-

ner here disclosed, I may utilize for the eyelet 14 a form shown in my copending application, Serial No. 349,749, filed January 6, 1920, wherein I have claimed the same per se. The eyelet 14 is shown detached in Fig. 2 and may comprise a sheet metal body 55 conveniently of circular form as shown provided with the oblate opening 16. Projecting rearwardly from the margins of the body are attaching prongs 18 by which the eyelet may be secured through the medium 60 of a washer 20 (see Fig. 1) to a curtain 22 or some similar member.

The face of the eyelet adjacent the opening 16 may be formed to provide at the extremities of the minor axis thereof protuberances 24 paralleling the major axis or longer dimension and sloping gradually downward in either direction from the extremities of the minor axis. The crest of these protuberances may be provided with 70 recesses 26 in the usual manner to seat the head of the turnbutton when it is turned in traversing relation to the eyelet to lock the parts of the fastening together. The button of the turnbutton is passed through 75 the opening and since the margins of the opening adjacent the longer extremity are countersunk relatively to the crests of the protuberances 24, the button may be readily turned toward the traversing position and 80 it will then ride along the protuberances 24 which act in the manner of cam rises and the head will thus press the eyelet rearwardly over the supporting body of the turnbutton, as will be clearly understood. 85 Provision is preferably made so that this action will cause the eyelet to bear against the support for the body of the turnbutton so that it is firmly held in position without danger of rattling and if the head of the 90 button is resiliently mounted either as described in my previous application above referred to or as herein disclosed, this action is facilitated and the eyelet is held 95 pressed in position by a resilient pressure 100 effectually preventing any rattling of the parts.

For this purpose the effective thickness of the eyelet, measured from the rearmost portion thereof (when in place on a curtain or the like) to the crests of the cam rises (really the bottoms of the recesses 26 when such are provided) is greater than the effec-

tive height of the body 10 and I have herein shown the metal of the eyelet adjacent the margin of the opening 14 extended rearwardly at either side of the minor axis 5 thereof provided with ears 28 which extend rearwardly through the opening in the curtain 22 which mates with the opening 16 in the eyelet and which are adapted to make contact with the support for the body 10 of 10 the turnbutton.

If we suppose the eyelet to be applied to the curtain 22 of an automobile it is obvious that it is desirable to roll the latter up and in any event the eyelet should be so 15 made as to project as little as possible from the surface of the curtain so that the parts will have a neat appearance and will not be likely to be bent or damaged. These considerations impose a practical limitation on the 20 length of the rearwardly projecting ears 28. An important feature of my invention, therefore, is the provision of a suitable button member in combination with an eyelet of the kind described to permit it to function 25 in the manner just described and also to obtain certain other advantages as will appear as the description proceeds.

Referring to Fig. 1, for this purpose the base 10 of the turnbutton which the member 30 encircles is made of very small height, thus reducing to a minimum the projection of the turnbutton member as a whole from the part to which it is attached. To facilitate making this base of low height the button proper 35 or head 12 is swivelled thereon and held thereto by resilient means disposed externally of the body 10 instead of interiorly thereof as is common and which means may be conveniently housed within the head 12. 40 Herein I have shown the head 12 as consisting of a suitable sheet metal stamping of cup-like form having a base opposed to the face of the body member 10, the latter being provided, if desired, with suitable crossed 45 positioning grooves 30 to receive in either position of the head the ribs 32 embossed in the base of the latter whereby to position the head either in alignment with the body or in traversing position thereto. The ribs and 50 grooves are preferably rounded so that the head 12 may, through use of its yieldable mounting presently to be described, be moved from one position to another by a mere turning action. The head 12 is adapted 55 to turn on a spindle 34 rising from the body, this spindle herein taking the form of a hollow rivet having a head 36 which may form a closure for the hollow head 12 and, in cooperation with the inturned margins 38 60 of the cup-like body thereof, in the normal position of the parts form the exterior wall of the head 12. As best shown in Fig. 7, the periphery of the opening defined by the inturned margins 38 may be bent inwardly to 65 provide a relatively extended bearing for

the head 36 of the rivet. Interposed between this head 36 and the base of the button member is a suitable spring such as the coil spring 40. The rivet is upset on the inner face of the hollow body or housing 10 and 70 it will be clearly understood that the head or button 12 is by this means yieldably and rotatably held upon the body 10. It will be noted that as far as the button member itself is concerned the body 10 need be of no substantial depth as it is required to accommodate only the turned over end of the rivet instead of the spindle and spring as is customary in certain types of turnbutton fasteners. In any turnbutton fastener, however, the head must be large enough to be grasped by the fingers and this space is herein utilized to accommodate the resilient means for positioning the head on the body. The overall dimensions of the fastener may 85 thus be reduced to a minimum so that it will project to a relatively small degree from the frame of the vehicle or other member to which it is attached.

This construction permits the eyelet 14 to 90 embrace the body 10 of the fastener and yet be pressed by the head against the support for such body without an undue increase in the thickness of the parts of the eyelet. Preferably the parts are so proportioned 95 that when the ears 28 make contact with the support for the body 10 (in the present instance a basal flange 42, presently to be referred to) the cam rises 24 will somewhat displace the head 12 toward the right in 100 Fig. 1, lifting it from its seat and compressing the spring 40. The parts are thus held pressed together by the spring pressure of the spring 40 and there is no lost motion which would lead to an unpleasant noise, 105 yet at the same time the eyelet is positively locked in its encircling position around the body 10 of the fastener by the head 12 in traversing position across the same. Preferably, however, such displacement does not 110 unseat ribs 32 from grooves 30 and therefore all the parts are locked together under the tension of the spring by interengaging portions, one of the ribs 32 being seated in the recesses 26 of the eyelet.

In the turnbutton member as here shown the head or button 12 may be conveniently made of the same cross section as the body 10, thus improving the appearance of the member particularly since the base of the 120 button or head 12 is provided with an extended bearing on the body which prevents disalignment of the same in any manner which would detract from appearance. The parts being thus more or less elliptical, the 125 head would be likely to turn in the fingers and to prevent this I slightly flatten the sides thereof as indicated in Fig. 5 and slope or undercut them slightly toward the rear of the fastener as shown in Fig. 6. This 130

flattening and undercutting may be so slight as to be practically unnoticeable in the completed fastener but nevertheless provide for a firm grip of the fingers thereon.

- 5 While the button member may be secured to a supporting surface such as the frame of the vehicle in any desired or known manner, I have herein disclosed a convenient method of utilizing a screw as the securing means.
- 10 Referring particularly to Figs. 1 and 4, the oblate body 10 of the button member is in the form of a hollow housing struck up from sheet metal and is provided with a basal flange 42 of general circular form and the diameter of this circle may correspond more or less closely to the longer dimension of the housing 10. For attaching this member there is provided an element having an enlarged head 44 and an attaching shank 46 in the form of a screw, rivet or the like. The head 44 rests against the flange 42 overlapping on either side of the shorter dimension of the housing 10 and may be secured in position by a rolled-over edge 48 of said flange embracing the edge of the head, as shown in Fig. 1. To prevent rotation of the securing member within the base member so that the whole may be handled as a unit, marginal portions 50 of the head 44 may be struck up in the form of prongs so as to enter the hollow housing 10, conveniently at the extremities of the longer diameter thereof, thus positioning the attaching member.

35 Claims—

1. A turnbutton fastener comprising, in combination, an oblate body, an eyelet adapted to encircle the same having an oblate opening and of greater thickness at the minor axis of said opening than the depth of the body, a head and resilient means exterior of the body for rotatably attaching the head thereto.
2. A turnbutton fastener comprising, in combination, an eyelet having an oblate opening, protuberances paralleling the major axis thereof and sloping downwardly toward their ends and a button member having a relatively shallow base adapted to be encircled by the eyelet, a rotatable head and means exterior to the base for yieldably pressing the head toward the base.
3. A turnbutton fastener comprising, in combination, an eyelet having provision providing a bearing therefor on a supporting member and a turnbutton having a low body to be embraced by the eyelet, a head and means for rotatably mounting it on the body including a spring housed in said head, the spring being tensioned when the parts are locked through displacement of the head by the eyelet which is supported by the member on which the body is carried.
4. A turnbutton fastener comprising, in combination, an eyelet having an oblate

opening and having cam rises on the face thereof along the longer sides of the opening and a turnbutton having a body to be embraced by the eyelet of effective height less than the effective thickness of the eyelet measured from the rearmost part thereof to the crests of said rises and having a head rotatably mounted on the body by means including a spring exterior to the body and adapted in the locked position of the parts to ride on said rises and be displaced thereby away from the body against the force of the spring.

5. A turnbutton fastener comprising, in combination, an eyelet having an oblate opening, rearwardly extending ears at the sides of the opening and cam rises on the face thereof along the longer sides of the opening and comprising also a turnbutton having a body to be embraced by the eyelet having an effective height less than the effective thickness of said eyelet measured between the ends of said ears and the crests of said rises and having a head rotatably mounted on the base by means including a spring exterior to the body and adapted in the locked position of the parts to ride on said rises and be displaced thereby away from the body against the force of the spring.

6. A turnbutton fastener comprising, in combination, an eyelet having portions to project rearwardly beyond the member carrying the eyelet and a turnbutton having a body to be embraced by the eyelet and of an effective height less than the effective thickness of the eyelet and having a head rotatably mounted on said body by means including a spring exterior to the body and adapted in the locked position of the parts to be displaced by the eyelet away from the body against the force of the spring.

7. A turnbutton fastener comprising an oblate body, a spindle rising therefrom, an oblate head rotatable about the spindle, a spring between the head and spindle normally pressing the head and body together and an eyelet to embrace said body and having an effective thickness greater than the effective height of said body whereby when the head is in traversing position across the eyelet it is displaced thereby away from the base against the force of said spring.

8. A turnbutton fastener as described in claim 7 wherein the eyelet and head are provided with rib and groove portions mating in the traversing position of the latter whereby the parts are positively locked under the tension of the spring.

9. A turnbutton comprising a base, a sheet metal cup-like head having a bottom fitting said base and an inturned margin providing a restricted open top for the cup, a spindle rising from the base passing through said bottom and having a head received by and

substantially closing the open top of the cup, and a spring interposed between said head and the bottom of the cup.

10. A turnbutton comprising a base, a sheet metal cup-like head having a bottom fitting said base and an inturned margin providing a restricted open top for the cup and bent inwardly at the periphery of said open top to provide an extended bearing, a spindle rising from the base, passing through the bottom and having a head received in said bearing and substantially closing the open top of the cup, and a spring interposed between said head and the bottom of the cup.
15. 11. A fastener including a basal flange portion, a hollow body embossed therefrom and means for securing the fastener including a plate received by said flange portion and having projections therefrom entering 20 the body portion.

12. A fastener including a circular flange portion and a hollow oblate portion arising therefrom and means for securing the fastener comprising a plate received by said flange portion having projections entering 25 the oblate portion thereby to prevent relative turning of the plate and the flange portion.

13. A fastener including a circular flange portion and a hollow oblate portion arising 30 therefrom having a major dimension substantially equal in length to the diameter of the circle and means for securing the fastener comprising a plate resting against the flange portion and having portions struck 35 from the margins thereof entering the oblate portion.

In testimony whereof, I have signed my name to this specification.

DAVID BOURQUE.
